TIME DELAY FUZE FOR A ROCKET

Kenneth L. Baker and Carl A. Axelson,
Washington, D. C.

Application August 29, 1947, Serial No. 771,288

7 Claims. (Cl. 102—71)

(Granted under Title 35, U. S. Code (1952), sec. 266)

This invention relates generally to a time delay fuze for use with an armor piercing rocket and more particularly to a time delay fuze in which means controlled by a predetermined amount of gas pressure produced as the propellant charge of the rocket motor burns is adapted to arm the fuze as the rocket is propelled along the trajectory toward the target, the firing of the fuze being controlled by firing means rotatably and slideably arranged within the fuze casing and adapted to be rotated to an armed position and thereafter moved longitudinally to a firing position in response to the sudden impact of the rocket with the target, at which time the firing means are locked in the firing position, whereupon the bursting charge within the rocket shell is detonated in predetermined time delayed relation with respect to the aforesaid impact of the rocket with the target, such time delay period being controlled by a delay charge arranged within the firing plunger slideably arranged within the fuze casing. Furthermore, on impact of the rocket with the target, the rocket is adapted to pierce the outer plates of a target such, for example, as a naval vessel, aircraft, or the like and to explode in the interior thereof whereby the force of the explosion is concentrated on the vital interior structural arrangement of the target.

More specifically the invention relates to a fuze for a rocket in which the firing means are maintained in a safe position during handling and transportation and in which arming thereof will not occur until after the rocket has been propelled from the launching rack and traveled a predetermined distance therefrom, the arming of the fuze occurring during the free flight of the rocket toward the target.

One of the objects of the present invention is the provision of a new and improved time delay fuze for a rocket in which the firing means of the fuze is locked in a safe position until the rocket is launched from a launching rack or tube, as the case may be, whereupon the firing means is released from an initial locked safe position and rotated to an armed position.

Another object of the present invention is the provision of a new and improved time delay fuze for a rocket in which a pressure controlled arming member is adapted to arm the fuze as the rocket is propelled toward the target.

Another object of the present invention is the provision of a new and improved fuze for a rocket in which arming means controlled by the pressure of combustion of the propellant is releasably and rotatably supported within the fuze casing and adapted to rotate the firing means from a safe position to an armed position when the arming means have been released by the pressure controlled means.

A further object of the invention is the provision of a new and improved fuze for a rocket having a rotatable arming member arranged therein adapted to be released and rotated to an armed position during the free flight of the rocket toward the target, and in which the firing means is slideably arranged therein and adapted to be locked in

2

the firing position upon impact of the rocket with the target.

Still another object of the present invention is the provision of a new and improved time delay fuze for a rocket in which the firing means thereof is adapted to be rotated from a safe position to an armed position, and thereafter to be moved longitudinally to a firing position and detonate the bursting charge within the rocket shell in predetermined time delay relation with respect to the aforesaid impact.

Still other objects, advantages and improvements will be apparent from the following description, taken in connection with the accompanying drawings, of which:

Fig. 1 is an elevational view of a rocket partially broken away and showing the fuze of the present invention secured thereto;

Fig. 2 is an enlarged longitudinal sectional view of the fuze of Fig. 1 and showing the fuze in a safe or unarmed condition;

Fig. 3 is a transverse sectional view of the fuze taken on the line 3—3 of Fig. 2;

Fig. 4 is a transverse sectional view of the fuze taken on the line 4—4 of Fig. 2;

Fig. 5 is a transverse sectional view of the fuze taken on the line 5—5 of Fig. 2, and showing the means for preventing further movement of the arming member after the member has been rotated to an armed position;

Fig. 6 is a fragmentary elevational view of the fuze partially broken away and in section and showing the shear pin for maintaining the rotatable arming member in an initial locked or safe position;

Fig. 7 is a view partially in longitudinal section and partially broken away showing the fuze in an armed condition;

Fig. 8 is a transverse sectional view of the fuze taken on the line 8—8 of Fig. 7;

Fig. 9 is a transverse sectional view of the fuze taken on the line 9—9 of Fig. 7;

Fig. 10 is a fragmentary longitudinal sectional view of the fuze showing the firing plunger in a firing position;

Fig. 11 is a transverse sectional view of the fuze taken on the line 11—11 of Fig. 10 and showing the arming member rotated to the armed position and a stop pin for preventing the further rotation thereof; and

Fig. 12 is a transverse sectional view of the fuze taken on the line 12—12 of Fig. 10 and showing a pair of detents for locking the firing plunger in the firing position.

Referring now to the drawings for a more complete understanding of the invention and more particularly to Fig. 1 thereof, there is shown thereon a rocket indicated generally by the reference character 10 comprising a motor tube 11 having the usual rocket motor generally indicated by the numeral 12 arranged therein. Secured to one end of the motor tube 11 in any suitable manner, preferably by threading the parts together, is a rocket head 13 comprising a shell 14 having arranged therein a bursting charge 15. Disposed in one end of the head and attached thereto as by an adapter 16 is the fuze of the present invention generally indicated by the reference character 17.

The rocket, Fig. 1, is a conventional type rocket and the motor thereof comprises the usual component parts such, for example, as a propellant 18, grid 19 for supporting the propellant within the tube 11, nozzle 21 adapted to direct the gas jet in the desired direction as the propellant burns and to provide for expansion of the gases in the exit cone of the nozzle, igniter 22, squib 23 arranged in operative relation with respect to the igniter, and conductors 24 attached to the squib and adapted to supply an electrical impulse thereto as the rocket is launched thereby to fire the squib and ignite the igniter which, in turn, ignites the propellant.

65

The motor tube 11 has secured to the other end thereof the usual stabilizing assembly generally indicated by the reference character 25 comprising a plurality of fins 26, the fins being attached to the tube in any suitable manner and extending radially therefrom and having a shroud 27 secured to the outer portions thereof. As the operation and structure of the aforesaid rocket is well-known to those skilled in the art, further detailed description of the operation and structural arrangement thereof is deemed unnecessary as the aforesaid rocket is disclosed for the purpose of more clearly illustrating the manner in which the fuze is armed in response to a predetermined amount of pressure created by the propellant 18 as the propellant burns.

The adapter 16 is threaded into the open end of the head 13, Figs. 1, 2 and 3, and has a centrally disposed threaded bore 28 formed therein for threaded engagement with the fuze 17, thus the fuze is secured to the adapter and extends a predetermined distance into the bursting charge 15.

The fuze of the present invention comprises a casing 29 composed of any material suitable for the purpose such, for example, as steel or the like and is provided with a centrally disposed bore 31, in which is arranged a plunger generally indicated by the numeral 32. The plunger comprises a body 33 having trunnions 34 and 35 respectively formed on the ends thereof which extend outwardly therefrom and slidably and rotatably support the plunger within the fuze casing 29. Arranged within a plurality of grooves 36 formed in the body 33 of the plunger are a plurality of anti-friction balls 37 adapted to engage the wall defining the bore 31, thereby to permit the plunger to move slidably and rotatably within the bore with no appreciable amount of friction between the wall defining the bore and the plunger when the plunger is released. The balls are maintained within the grooves 36 by a washer 38 and a collar 39 surrounding the trunnion 35 and secured to the body 33 of the plunger in any suitable manner such, for example, as by a pin 41.

As shown on Figs. 2, 7 and 10 the plunger has formed therein a bore or well 42 having arranged therein a delay element generally indicated by the numeral 43 and comprising a casing 44 within which is disposed a delay charge 45. One end portion of the delay charge is in proximate space relation with respect to one end of a detonator 46 arranged in a reduced bore 47 and in communication with the bore 42 in the plunger, the other end of the detonator being in substantial abutting engagement with a lead-out charge 48 arranged in a transverse bore 49 disposed within the body 33 of the plunger. The other end of the delay charge is arranged in spaced relation with respect to a primer indicated by the reference character 50 and adapted to fire the delay charge by way of bore 51 and passages 52 disposed within the casing 44.

The primer 50 is disposed within a well 53 formed in a nipple 54 and having threaded engagement with the threaded portion of bore 42, the primer being clamped between the member 44 and nipple 54, Fig. 2. Threaded into the nipple 54 is a casing 55 having an explosive cap 56 arranged therein and adapted to be fired as the rocket strikes the target. Arranged within a bore 57 formed in the nipple 54 is an annular member 58 having a centrally disposed opening extending therethrough. Disposed in the opening and secured to the annular member 58 by a shear pin 60 is a firing piston 59 comprising a head 61 and a striker 62, the striker being adapted to strike the primer 50 with sufficient force to cause firing thereof when the cap 56 has been fired upon impact of the rocket with the target. It will be understood, however, that when the cap 56 is fired, the force of the explosion therefrom will be sufficient to sever the shear pin and drive the piston toward the primer 50 and the striker 62 thereon will strike the primer 50 with suffi-

cient force to cause explosion thereof thus igniting the delay charge and firing the detonator.

An anti-creep device 63 comprising a skirt 64 is arranged about a portion of the trunnion 35 and about an enlarged head 65 formed on the nipple 54, the anti-creep device being maintained on the trunnion and head by a flange 66 formed thereon and clamped between the head 65 and a flanged portion 67 formed on the casing 55. As best shown on Fig. 2 the skirt 64 seals a pair of diametrically arranged ports 68 formed in the head 65, the ports being in communication with the bore 57, the purpose of which will be more fully described hereinafter. Premature longitudinal movement of the plunger 32 after rotation thereof is prevented by a plurality of tabs 80 formed on the skirt 64 and extending outwardly therefrom and adapted to engage a disc 69. Upon impact these tabs are bent inwardly sufficiently to release the plunger for longitudinal movement.

The disc 69 has a centrally disposed opening 70 therein and is arranged within an enlarged portion 71 of bore 31, the disc being maintained within the aforesaid enlarged portion by a plug 72 having threaded engagement therewith. It will be understood, however, that when the plunger has been released and moved to a firing position, Fig. 10, upon impact of the rocket with a target, the plunger is forced toward a firing pin 73. The firing pin is secured to the plug 72 in any suitable manner such, for example, as being pinned thereto and having a striker 74 formed thereon adapted to extend into a recess 75 arranged in plug 72 in such a manner as to have firing engagement with the explosive cap 56 when the plunger has been moved a predetermined amount in response to the aforesaid impact of the rocket with a target. As the plunger is moved to the firing position the anti-creep device attached thereto is moved through opening 70 formed in disc 69 a predetermined amount and upon firing of the cap 56 in the aforesaid manner the skirt 64 of the anti-creep device is distorted or bulged as at 76 at two points opposite ports 68, Fig. 10, in response to the force of the explosion partially directed thereagainst by way of the aforesaid bore 57 and ports 68, it being understood, that the explosive force is also directed against the head 61 of the firing piston 59, the divided force of the aforesaid explosion being controlled by a deflector 77 arranged in the bore 57. Thus the force of the explosion is sufficient not only to cause the skirt 64 to be bulged in the aforesaid manner but also to drive the piston 59 rearwardly with sufficient force to cause the shear pin 60 to be severed whereupon the striker 62 formed thereon will be driven into firing engagement with the primer 50.

When the plunger has been moved longitudinally to the firing position in response to the set-forward force as the rocket strikes the target, the skirt 64 will be bulged as heretofore described, the bulged portions thereof being adapted to engage the disc 69 and prevent reverse movement of the plunger from the forward position thereof before it is locked by the detent locking mechanism, Fig. 10. When this occurs, a pair of diametrically disposed spring controlled locking detents 78 slideably arranged within bores formed in the casing are brought into axial alignment with their respective slots 79 formed in the plunger 32, the detents being urged therein by a pair of springs 81 respectively arranged within the aforesaid bores and in engagement with the detents 78, Figs. 4, 9 and 12, thereby locking the plunger permanently in the firing position and preventing further longitudinal and rotative movement thereof.

As shown on Fig. 4, the detents 78 are adapted to engage and ride on the outer periphery of the plunger 32 when the plunger is rotated from a safe to an armed position, the detents being spaced axially substantially 90° from the axially arranged slots 79 in the plunger when the plunger is in a safe position. As shown on Figs. 7 and 9, the plunger 32 has been released and ro-

tated from the safe position to an armed position. With particular reference to Fig. 9 the detents 78 remain in engagement with the outer periphery of the plunger after the plunger has been rotated from the safe position to an armed position, a movement of substantially 90°, the slots 79 therein are thus brought into longitudinal spaced alignment with respect to the detents 78 and upon impact of the rocket with the target the plunger is driven longitudinally forwardly to the firing position, Fig. 10, and locked in the firing position by the aforesaid detents 78.

As shown on Figs. 2, 3, and 5 a pair of diametrically disposed pins 82 are secured to the casing 29 in any suitable manner and extend into the bore 31 a predetermined amount, the respective ends thereof having abutting engagement with the forward end of the plunger thus preventing longitudinal movement of the plunger within the bore 31 until the plunger has been rotated substantially 90° by an arming member as will be hereafter more fully described. It will be understood, however, that when the plunger has been rotated substantially a quarter of a turn, the ends of the pins are brought into spaced longitudinal alignment with a pair of complementary longitudinally arranged slots 83 formed in the plunger thereby to permit free passage of the plunger with respect to the pins as the plunger is moved longitudinally within the bore 31 to the aforesaid firing position. It will be further understood, that when the plunger 32 is rotated substantially 90° the detents 78 are brought into spaced longitudinal alignment with a pair of slots 79, such rotative movement also being adapted to bring the slots 83 into spaced longitudinal alignment with pins 82 thereby to permit longitudinal movement of the plunger to the firing position and also providing means for locking the plunger in the firing position upon impact of the rocket with the target.

As shown most clearly on Figs. 2 and 7 of the drawings there is arranged within the casing 29 an arming device generally indicated by the numeral 84 and comprising a bearing member 85 disposed within an enlarged recess 86 formed in one end of the casing 29, the bearing member being maintained therein by an annular nut 87 having abutting engagement with a shoulder 88 formed on the bearing member 85 and adapted to be threaded into the recess 86. Disposed within the bearing member 85 and rotatably supported with respect thereto is a normally locked spring actuated rotor 89 adapted to rotate the plunger 32 to an armed position when released. The rotor is maintained within the bearing member by an annular disc 91 secured to the member in any suitable manner such, for example, as by crimping one end portion of the member about the annular disc Figs. 2, 6, 7 and 10.

The rotor 89 is rotatably supported by the disc 91 and a sleeve 92, releasably and slideably arranged within a bore 93 disposed in the rotor 89 and an opening 94 in the member 85, the sleeve 92 being releasably supported by a shear pin 95 extending through openings 96 in the sleeve 92 and complementary openings 97 arranged in the bearing member.

A drive pin 98 extends through a slot 99 formed in trunnion 34 and into corresponding openings 101 arranged in the rotor 89, the pin also extending through a pair of slots 102 in sleeve 92. By this arrangement, a driving connection is provided between the plunger 32, arming member 89 and sleeve 92 by pin 98 and rotative movement will be imparted to these component parts when the shear pin 95 is severed, such rotation being imparted thereto by a spring 103 surrounding the rotor 89 and having one end thereof anchored therein and the other end anchored in the bearing 85. It will be understood, that when the shear pin 95 has been severed the rotor, plunger, and sleeve will be rotated a predetermined amount such, for example, as approximately 90°, the rotation thereby being controlled by a stop pin 104 se-

cured to the casing 29 in any suitable manner and extending through a recess 105 in the bearing 85 and into a slot 106 formed in the rotor 89 Figs. 2, 5, and 11. A shoulder 107, Figs. 5 and 11, on the rotor and formed by the wall defining the slot 106 thereof is adapted to engage the pin 104 and prevent further rotation of the aforesaid rotatable elements when the elements have been released and rotated substantially 90° in response to the action of spring 103.

When the plunger 32 has been rotated substantially 90° in the aforesaid manner the lead-out charge 48 therein is brought into spaced longitudinal alignment with respect to a pair of diametrically disposed booster charges 108 arranged within complementary recesses 109 formed in casing 29 as clearly shown on Fig. 7. A pair of additional diametrically disposed booster charges 111 are respectively arranged within recesses 112 formed in the casing 29 in proximate spaced relation with respect to the charges 108 and adapted to be fired thereby. The aforesaid charges 108 and 111 are maintained within their respective recesses by a retaining cup 113 enclosing the charges and having threaded engagement with the casing 29.

As shown on Fig. 10 the plunger 32 has been moved to a firing position in response to the impact of the rocket with a target and locked therein by the aforesaid detents 78. When this occurs a continuous firing train is provided from the cap 56 to the booster charges 108 by way of cap 56, primer 50, delay charge 45, detonator 46, lead-out charge 48 and booster charges 108 and 111 which are adapted to fire the bursting charge 15 arranged within the shell 14 of the rocket head 13. It will be understood, however, that the bursting charge 15 will not be fired by the aforesaid booster charges until a predetermined period of time has elapsed after the rocket strikes the target, the time delay period being controlled by the delay charge 45 thus permitting the rocket to pierce the outer structure or plates of the target and enter the interior thereof before the bursting charge 15 is fired.

A plug generally indicated by the reference numeral 114 is threaded into a well 115 formed in one end of the casing 29 and comprises an end wall 116 having a centrally disposed opening 117 arranged therein and an annular flange 118 formed thereon. Secured within the opening 117 as by threaded engagement therewith is a valve 119 comprising a casing 121 having a centrally disposed bore 122 extending partially therethrough in which is arranged a ball valve 123 adapted to normally seal a restricted bore 124, the bore being in communication with the bore 122. The ball valve 123 is urged in sealing engagement with respect to bore 124 by a spring 125, one end thereof being in abutting engagement with the ball valve, and the other end in engagement with a plug 126 secured in the casing 121 as by threaded engagement therewith.

A pair of diametrically disposed exhaust ports 127 are arranged within the casing 121 and in communication with the bore 122, the ports also being in communication with a chamber 128 provided between the end wall 116 on plug 114 and an end wall 129 formed on a cup-shaped member 131 arranged within the well 115 and maintained therein by the aforesaid plug 114. Extending transversely through the casing 121 and in communication with bore 124 is an inlet port 132, thus providing means whereby the gas pressure created by the propellant 18 as the propellant burns is admitted therethrough and into chamber 128 when the pressure within the motor tube 12 has increased sufficiently to overcome the tension of the spring 125 and unseat the valve 123.

Clamped between a shoulder 133 formed within the well 115 and the member 131 by the plug 114 is a flexible diaphragm 134 having a substantial portion thereof reinforced by a disc 135 secured thereto in any suitable manner preferably as by soldering the parts together. It will

be understood, however, that the diaphragm is adapted to be expanded in response to a predetermined amount of pressure exerted thereon, such pressure being created in the aforesaid manner and entering into a chamber 136 provided between the wall 129 and the diaphragm by way of an orifice 137 formed in the wall 129 and in communication with the aforesaid chambers 128 and 136. It will be further understood, that when a sufficient amount of pressure has entered into chamber 136 by way of orifice 137, the diaphragm will be forced into engagement with sleeve 92 by the aforesaid pressure, whereupon the sleeve 92 is driven inwardly by the expansion of the diaphragm sufficiently to cause the shear pin 95 to be severed due to the frangibility thereof and the shearing action exerted thereon as the sleeve 92 is moved inwardly with respect thereto in the aforesaid manner, the inward movement of the sleeve being permitted by the slots 83 formed therein.

Clamped between an enlarged head 138 formed on the valve casing 121 and the end wall 116 of plug 114 is a screen or filter member 139 adapted to permit the aforesaid gas pressure to enter into the chamber 128 by way of valve 119 but to exclude foreign matter therefrom such, for example, as the particles of combustion produced as the propellant 18 burns. The head 138 is also adapted to clamp a grip member 141 to the plug 114.

The aforesaid arming of the fuze will occur as the rocket is propelled along the trajectory by the functioning of the motor 17 as is well known to those skilled in the art, it being understood, however, that the propellant charge of the rocket motor is ignited in the usual manner as the rocket is launched from the launching rack or tube (not shown), as the case may be. As the rocket is propelled along the trajectory by the rocket motor a sufficient amount of gas pressure enters into the chamber 128 by way of valve 119 as the propellant charge burns and causes expansion of the diaphragm 134, such expansion being sufficient to drive the sleeve 92 inwardly with sufficient force to cause the shear pin 95 to be severed.

When the shear pin has been severed, the arming member 89 is released and rotated substantially 90° to an armed position, Fig. 7, by the action of spring 103, further rotation thereof being prevented by stop pin 104. It will be understood, however, that as the arming member is rotated, rotation of the plunger 32 is effected by the drive pin 98 secured to the arming member and extending through slot 99 formed in trunnion 34 of the plunger. When this occurs, the lead-out charge 48 is brought into spaced longitudinal alignment with the booster charges 108, Fig. 7, and the slots 83 are brought into spaced longitudinal alignment with pins 82 thus permitting free longitudinal movement of the plunger to a firing position upon impact of the rocket with the target, the pins 82 preventing longitudinal movement of the plunger until the plunger has been moved to an armed position in the aforesaid manner. As the rocket strikes the target the plunger is moved to the firing position in response to the set-forward force applied thereto, whereupon the explosive cap 56 is fired by the firing pin 73, the force of the explosion being sufficient to cause the skirt 64 to be bulged as at 76 and hold the plunger momentarily, thereby to permit the locking detents 78 to be urged into their respective slots 79, thus locking the plunger in the firing position. As the cap 56 is fired by the firing pin 73, the force of the explosion is sufficient not only to bulge the skirt 64 but also to sever the shear pin 60 and drive the piston toward primer 50, whereupon the striker 62 thereon will strike the primer with sufficient force to cause explosion thereof, the flash therefrom igniting the delay charge 45 thereby exploding the detonator 46 when a predetermined period of time has elapsed. The detonator fires the lead-out charge 48 and the booster charges 108 are fired thereby which initiates firing of the auxiliary booster charges 111 and concurrently therewith the bursting charge 15 is fired and fragmentation of the shell occurs.

Briefly stated in summary, the present invention comprises the provision of a new and improved time delay fuze for an armor piercing rocket in which means are provided for firing an explosive charge arranged within the rocket shell in predetermined time delayed relation with respect to impact of the rocket with the target, and in which the arming means is controlled by gas pressure formed by combustion of the rocket propellant and adapted to release a rotor within the fuze as the rocket is propelled along the trajectory thereby to rotate a firing plunger from an initial safe position to an armed position, the plunger thereafter being adapted to be moved longitudinally to a firing position and locked therein as the rocket strikes the target, and in which means are provided for detonating the bursting charge arranged within the rocket shell when a predetermined period of time has elapsed after impact of the rocket with the target.

While the invention has been described with reference to a preferred example thereof which gives satisfactory results, it will be obvious to those skilled in the art to which the invention pertains, after understanding the invention, that various changes and modifications may be made without departing from the spirit and scope of the invention, and it is intended therefore, in the appended claims, to cover all such changes and modifications.

The invention herein described and claimed may be manufactured and used by or for the Government of the United States of America for governmental purposes without payment of any royalties thereon or therefor.

What is claimed as new and desired to be secured by Letters Patent of the United States is:

1. A time delay fuze for a rocket comprising a casing, a pair of booster charges arranged within said casing, an arming member releasably and rotatably supported within said casing in a safe position and adapted to be rotated to an armed position when released, means including a device slideably arranged within said arming member and releasably secured to the casing for maintaining the arming member in said safe position, means secured to the casing and the arming member for rotating the arming member a predetermined amount to said armed position when the arming member is released, flexible means sealed to the casing and normally spaced from said device for moving said device sufficiently to release the device from the casing as the flexible means is moved into engagement with the device in response to the pressure applied to the flexible means as the rocket travels along a trajectory, a firing plunger rotatably supported within the casing and adapted to be rotated to an armed position and moved longitudinally to a firing position upon impact of the rocket with a target, a bifurcated portion on said plunger, driving means on said arming member and slideably disposed within said bifurcated portion for rotating the plunger to said armed position thereof when the arming member is rotated said predetermined amount, exposure means including a time delay element arranged within said plunger for firing said booster charges when a predetermined period of time has elapsed after said impact, and means on the casing for firing said explosive means upon forcible engagement therewith as the plunger moves to said firing position in response to said impact.

2. A time delay fuze for a rocket comprising a casing having a pair of diametrically disposed recesses formed therein, a pair of booster charges respectively arranged within said recesses, an arming member releasably and rotatably supported within said casing in an initial safe position and adapted to be rotated to an armed position when released, means including a shearable member secured to said casing and operatively connected to said arming member for maintaining the arming member in said initial safe position and adapted to release the arming member when severed in response to a predetermined pressure applied thereto, pressure controlled means sealed to the casing and movable into engagement with said arming member by pressure applied thereto from the combustion of the

rocket propellant as the rocket travels along a trajectory for applying said pressure to the shearable member, spring means secured to the casing and arming member for rotating the arming member to said armed position as said shearable member is severed, spring urged valve means on the casing in communication with said propellant and said pressure controlled means for applying said pressure to the pressure controlled means when the pressure from said propellant has reached a predetermined value, a firing plunger rotatably supported within the casing and adapted to be rotated to an armed position by said arming member and moved longitudinally to a firing position upon impact of the rocket with a target, a bifurcated portion on said plunger, drive means on the arming member and disposed within said bifurcated portion for rotating the plunger to said armed position as the arming member is released, explosive means including a time delay element arranged within said plunger for firing said booster charges when a predetermined period of time has elapsed after said impact, means on the casing for firing said explosive means when the plunger is moved to said armed position and the explosive charge is driven into firing engagement therewith in response to said impact, a plurality of yieldable tabs carried by said plunger and extending outwardly therefrom, and means on said casing in the path of travel of said tabs for preventing said longitudinal movement of the plunger until said impact.

3. A time delay fuze for a rocket comprising a casing, a pair of booster charges arranged within said casing, an arming member releasably and rotatably supported within said casing in an initial safe position, a sleeve disposed within said arming member and slideably arranged within said casing for supporting the arming member within the casing, shearable locking means secured to the casing and sleeve for releasing the arming member for rotation to said armed position when the locking means is severed in response to a predetermined amount of movement of said sleeve, spring means secured to the casing and arming member for rotating the arming member to said armed position as the arming member is released, a firing plunger rotatably supported within the casing and adapted to be rotated to an armed position by said arming member and moved longitudinally to a firing position upon impact of the rocket with a target, said plunger having a slot formed therein, a drive pin secured to the arming member and slideably disposed within said slot formed in said plunger for rotating the plunger to said armed position in response to rotation of the arming member, explosive means carried by said plunger and including a time delay element for firing said booster charge when a predetermined period of time has elapsed after the explosive means is fired, means on the casing for firing said explosive means upon forcible engagement therewith when the plunger is moved to said firing position, a plurality of yieldable elements carried by and extending outwardly from the plunger, and means on said casing in the path of travel of said elements for preventing said longitudinal movement of the plunger to said firing position until said impact.

4. A time delay fuze for a rocket comprising a casing, a pair of booster charges arranged within said casing, a normally locked firing plunger releasably and rotatably arranged within the casing and adapted to be rotated from an initial safe position to an armed position when released and to be moved to a firing position in response to said impact, said plunger having a slot formed therein, a shear pin secured to said casing and disposed within said slot for locking the plunger against rotation to said armed position until said pin is severed in response to a predetermined amount of pressure applied thereto, an arming member rotatably supported within the casing and locked against rotation by said shear pin and adapted to be rotated a predetermined amount when said shear pin is severed, sleeve means releasably supported within the arming member by said shear pin for severing the pin in response to said pressure thereon as the sleeve is moved

a predetermined amount, a flexible diaphragm sealed to the casing and movable into engagement with said sleeve by the gas pressure of combustion of the rocket propellant for moving the sleeve said predetermined amount, means on said arming member and secured to the casing for rotating the arming member said predetermined amount, means secured to the arming member and traversing said slot for rotating the plunger from said initial safe position to said armed position when the arming member is released and rotated said predetermined amount, means including a time delay element arranged within the plunger for firing said booster charge in time delayed relation with respect to said impact, and means on the casing for firing said last named means upon forcible engagement therewith as the plunger is moved to said firing position in response to said impact.

5. A fuze for a rocket comprising a casing, a normally locked firing plunger releasably and rotatably arranged within the casing and adapted to be rotated from an initial safe position to an armed position when released and to be moved to a firing position upon impact of the rocket with a target, a bifurcated portion on said plunger, shearable locking means secured to said casing and traversing said bifurcated portion for locking the plunger against rotation to said armed position until the shearable means is severed in response to a predetermined amount of pressure applied thereto, sleeve means releasably supported within the casing by said shearable locking means for applying said pressure thereto, means sealed to the casing and movable into engagement with said sleeve means by gas pressure from combustion of the rocket propellant for applying said pressure to the sleeve means, arming means rotatably supported within the casing and connected for rotation with the plunger and adapted to be rotated a predetermined amount when said locking means is severed, means on said arming means and secured to the casing for rotating the arming means said predetermined amount, means secured to the arming means and traversing said bifurcated portion for rotating the plunger from said initial safe position to said armed position when the plunger is released and the arming means is rotated said predetermined amount, explosive means carried by said plunger, and means on the casing and normally spaced from said plunger for firing said explosive means upon forcible engagement therewith when the plunger is moved to said firing position in response to said impact.

6. A time delay fuze for a rocket comprising a casing, a pair of booster charges arranged within said casing, rotor means releasably supported within said casing and adapted to be rotated a predetermined amount when the rotor means is released, spring means on said rotor means and secured to the casing for rotating the rotor means said predetermined amount as the rotor means is released, a shear pin secured to the casing and operatively connected to said rotor means for releasably supporting the rotor means within the casing and adapted to prevent rotation thereof until said shear pin is severed, means including a flexible diaphragm sealed within the casing and movable by gas pressure of combustion of the rocket propellant for causing the shear pin to be severed as said diaphragm is forcibly driven into engagement with the rotor means in response to an increase in said pressure, a plunger operatively connected to the rotor means for rotation from an initial safe position to an armed position as the rotor means is rotated said predetermined amount, said plunger being adapted to be moved longitudinally to a firing position upon impact of the rocket with a target, a bifurcated portion on said plunger, means on the rotor means and disposed within said bifurcated portion for rotating the plunger from said initial safe position to said armed position as the rotor means is released and rotated said predetermined amount, said plunger being adapted to be moved longitudinally to a firing position upon impact of the rocket with a target, a bifurcated portion on said plunger, means on the plunger in engagement with the casing for releasably locking the plunger in said armed position until said impact, explosive means including a time delay element arranged with

the plunger for firing said booster charges in time delayed relation with respect to said impact, and means on said casing for firing said explosive means upon forcible engagement therewith when the plunger is released and driven into said firing position in response to said impact.

7. A time delay fuze for a rocket comprising a casing, a pair of booster charges arranged within said casing, a plunger rotatably and slideably supported within the casing in an initial safe position and adapted to be rotated to an armed position as the rocket travels along a trajectory, said plunger being adapted to be moved slideably from said armed position to a firing position in response to impact of the rocket with a target, a pair of stop pins secured to said casing, complementary means on the plunger in engagement with said stop pins for preventing said sliding movement of the plunger until the plunger has been rotated to said armed position, rotatable arming means releasably secured to said casing and rotatively connected to the plunger and adapted to be rotated a predetermined amount when released, a bifurcated portion on said plunger, a shear pin secured to the casing and disposed within said bifurcated portion for releasing the arming means and plunger when the pin is severed in response to a predetermined pressure applied thereto, a flexible diaphragm sealed within the casing and movable into engagement with said arming means by gas pressure of combustion of the rocket propellant thereon for applying said pressure to the shear pin, drive means on said
